UNITED STATES PATENT OFFICE.

REUBEN P. GRANT, OF BOSTON, MASSACHUSETTS, ASSIGNOR TO BECKWITH BOX TOE COMPANY, OF BOSTON, MASSACHUSETTS, A CORPORATION OF MASSACHUSETTS.

FEED-ROLL FOR LEATHER-SKIVING MACHINES, &c.

No. 887,625.

Specification of Letters Patent.

Patented May 12, 1908.

Application filed June 24, 1907. Serial No. 380,566.

To all whom it may concern:

Be it known that I, REUBEN P. GRANT, of Boston, in the county of Suffolk and State of Massachusetts, have invented certain new and useful Improvements in Feed-Rolls for Leather-Skiving Machines, &c., of which the following is a specification.

This invention relates particularly to machines for skiving box-toe blanks, and as here shown is embodied in a machine, the essential parts of which are a splitting knife and a pair of feed rolls, the nip of which is arranged to present the leather to be skived to the edge of the splitting knife, the bed roll having a depression in its periphery corresponding in contour to the skived blank to be produced, and constituting a matrix, while the companion or pressure roll is arranged to press a sheet of leather against the bed roll, and cause it to conform closely to the matrix, the action of the machine being to produce a blank which conforms accurately to the shape of the matrix, the portion of the leather which constitutes the blank, sinking into the matrix under the action of the pressure roll, so that all portions of the sheet that are not pressed into the matrix, are cut away in the form of a skiving, leaving a blank which is perfectly skived around its entire margin.

The invention has for its object to provide an improved construction of pressure roll adapted to cause that portion of the material which constitutes the skived blank, to conform accurately to the matrix, and to feed the material positively, without liability of slippage of the pressure roll on to the material.

The invention consists in the improvements which I will now proceed to describe and claim.

Of the accompanying drawings forming a part of this specification,—Figure 1 represents a sectional view of a portion of a skiving machine embodying my invention. Fig. 2 represents a view similar to a portion of Fig. 1, illustrating a different stage of the skiving operation. Fig. 3 represents a sectional view of the completed skived blank. Fig. 4 represents a view of a portion of the pressure roll, part of said view being in section on line 4—4 of Fig. 1. Figs. 5 and 6 represent perspective views of the sections which form the face of the pressure roll.

The same letters of reference indicate the same parts in all the figures.

In the drawings *a* represents a leather splitting knife, which may be of any suitable character, and may be either fixed, or movable as a band knife, the knife being here shown as affixed to a suitable support *b*.

c represents a bed roll, in the periphery of which is a depression *d* which constitutes a matrix, said depression being of appreciable depth at its central portion, and its depth gradually decreasing to its margin, where it joins the concentric portion of the periphery of the roll, as shown in Fig. 1.

The feed or pressure roll which coöperates with the bed roll in pressing one side of a sheet of leather or other material *e* into the matrix, and in forcing the sheet *e* edgewise against the splitting knife, has an acting face or periphery, which, in this embodiment of my invention, is formed by a series of rigid *f* collars and a series of compressible, preferably elastic, collars *g*, said collars *f* and *g* alternating with each other, and being mounted upon a cylindrical body or shaft *h*, which is preferably tubular, and constitutes a hub adapted to be mounted on a fixed journal. The sections *f*, which are composed of any suitable metal, are provided with sharp-pointed teeth or serrations *f'*, forming the perimeters of the sections, said sections being rigidly affixed to the body *h* by means of a spline *i* engaging corresponding grooves or seats formed in the exterior of the body *h*, and in the inner edges of the sections *f*.

The sections *g*, which are preferably composed of vulcanized rubber having a considerable degree of elasticity, are interposed between the sections *f*, and their perimeters are normally flush with the points of the teeth *f'*, so that the points of the teeth and the perimeters of the sections *g* bear simultaneously on one side of the sheet *e*. The two rolls are so arranged relatively to the splitting knife that they nip the sheet *e*, and present it to the edge of the knife in the direction required to cause the skiving action. The said rolls are so spaced apart that when the matrix *d* is wholly at one side of the nip of the rolls, as shown in Fig. 2, the teeth *f'* will indent one side of the sheet *e* somewhat deeply, as shown in Fig. 2, the corresponding portions of the elastic sections *g* yielding,

and being compressed by the sheet e , and at the same time maintaining a feeding engagement with the sheet. When the matrix is brought by the rotation of the bed roll into 5 the nip of the rolls, as shown in Fig. 1, the side of the sheet bearing on the bed roll is pressed by the conjoint action of the serrated sections and the elastic sections into the matrix, the elastic sections expanding and 10 aiding materially in pressing one side of the sheet into close contact with the surface of the matrix, the yielding sections at the same time maintaining their feeding engagement. It will be seen by reference to Fig. 1 that 15 while the deeper portions of the matrix are in the nips of the rolls, the depth of penetration of the opposite side of the sheet by the teeth f' is less than when the matrix is wholly at one side of the nip of the roll. My 20 improved roll is therefore characterized by the fact that its acting face is formed by the perimeters of alternating rigid and compressed sections which simultaneously exert a feeding action on the material, the compressible sections also acting to force one 25 side of the material against the face of the matrix. An effective feeding engagement is therefore constantly maintained between the feed roll and the material being fed, there 30 being no non-rotating parts in the spaces between the serrated sections f .

Heretofore in skiving machines of this character, the feed roll provided with serrated sections spaced apart, has been accompanied by non-rotating spring-pressed arms 35 or fingers projecting into the spaces between the serrated sections, and bearing yieldingly on one side of the material. These fingers, however, do not partake of the rotary movement of the feed roll and they therefore exert a frictional drag on the material, which is 40 not the case with the elastic sections g of my improved feed roll.

The relative thickness of the sections f and 45 g may be varied, the section g being considerably thicker, if desired, than the sections f . In assembling the sections on the body h , the elastic sections may be subjected to compressive pressure which will cause them to 50 bulge laterally into the spaces between the teeth of the rigid sections, thereby increasing the area of feeding surface afforded by the

elastic sections. Another important function of the elastic sections g is that of forcing the skiving e' off from the teeth f' as the 55 skiving passes from the nip of the rolls, this being accomplished by the expansion of the material of the said sections. The skived blank e' passes at the opposite side of the knife, as shown in Fig. 1.

My improved feed roll is not limited to use in connection with a splitting knife and a bed roll having a matrix, although as above set forth its characteristics are particularly adapted for use in connection with said parts. 60

I claim:

1. A feed roll the face of which is formed by the perimeters of alternating rigid and elastic sections the rigid sections being serrated to engage the material being fed, and the elastic sections adapted to be compressed by said material.

2. A feed roll the face of which is formed by alternating rigid and elastic sections, the rigid sections being serrated, and the elastic sections normally substantially flush with the points of the serrations.

3. A feed roll comprising a supporting body, a series of spaced rigid serrated sections affixed to the body, and a series of elastic sections alternating with the rigid sections.

4. In combination, a bed roll, and a feed roll opposed to the bed roll and having a face formed by the perimeters of alternating rigid and elastic sections, the rigid sections being serrated, and the elastic sections normally substantially flush with the points of the serrations.

5. In combination, a bed roll having a 90 matrix in its periphery, a feed roll opposed to the bed roll and having a face formed by the perimeters of alternating rigid and elastic sections, the rigid sections being serrated, and the elastic sections normally substantially flush with the points of the serrations, and a splitting knife arranged to coöperate with said rolls.

In testimony whereof I have affixed my signature, in presence of two witnesses.

REUBEN P. GRANT.
